CLAIM

The ornamental design for a collet nut torque adapter, as shown and described.

DESCRIPTION

FIG. 1 is a top perspective view of the collet nut torque adapter according to the present invention.

FIG. 2 is a front elevational view of the collet nut torque adapter of FIG. 1.

FIG. 3 is a back elevational view of the collet nut torque adapter of FIG. 1.

FIG. 4 is a right-side elevational view of the collet nut torque adapter of FIG. 1.

FIG. 5 is a left-side elevational view of the collet nut torque adapter of FIG. 1.

FIG. 6 is a top plan view of the collet nut torque adapter of FIG. 1; and,

FIG. 7 is a bottom plan view of the collet nut torque adapter of FIG. 1.
